UNITED STATES PATENT OFFICE

163,531

CORN POPPER OR SIMILAR ARTICLE

Donald F. McCarron, St. Louis, Mo., assignor to
Knapp-Monarch Company, St. Louis, Mo., a
corporation of Delaware

Application November 5, 1949, Serial No. 5,891

Term of patent 14 years

(Cl. D81—10)

To all whom it may concern:

Be it known that I, Donald F. McCarron, a citizen of the United States and a resident of the city of St. Louis, State of Missouri, have invented a new, original, and ornamental Design for a Corn Popper or Similar Article, of which the following is a specification, reference being had to the accompanying drawing, forming a part thereof, in which:

Figure 1 is a perspective view of a corn popper or similar article, showing my new design.

Figure 2 is a side elevational view of the corn popper on a reduced scale.

The dominant feature of the design resides in the portion shown in full lines on the drawing.

I claim:

The ornamental design for a corn popper or similar article, as shown and described.

DONALD F. McCARRON.
